UNITED STATES PATENT OFFICE.

JOHN W. LATIMER, OF LAKewood, OHIO.

OVEN-WALL CONSTRUCTION.

Application filed July 16, 1923. Serial No. 651,997.

To all whom it may concern:

Be it known that I, JOHN W. LATIMER, a citizen of the United States, residing at Lakewood, in the county of Cuyahoga and 5 State of Ohio, have invented a certain new and useful Improvement in Oven-Wall Constructions, of which the following is a full, clear, and exact description, reference being had to the accompanying drawings.

10 This invention relates to wall or partition construction and has for its general object to provide a wall or partition which is light in weight but which will, nevertheless, be efficient in the matter of insulating against 15 heat and cold the spaces enclosed or separated thereby. A further object of the invention is to provide a wall or panel construction which is durable and in which the exterior surface may be of metal, with inter- 20 posed braces or stanchions to which the exterior wall sections may be conveniently secured and without the necessity for employing a metal-to-metal contact between 25 such external surfaces. My invention is par- ticularly adapted for the construction of ovens, such as core, enameling and heat- 30 treating ovens.

I accomplish the foregoing object and more limited objects which will appear 35 hereinafter, in and through the construction and arrangement of parts shown in the drawings, wherein Fig. 1 represents a horizontal sectional view through the corner of a room or building having my invention applied thereto; Fig. 2 a vertical section on the line 2—2 of Fig. 1; and Fig. 3 a detail in horizontal section showing the manner in which contiguous panels may be 40 conveniently united.

45 Describing by reference characters the various parts illustrated herein 1 denotes the outer and 2 the inner sheet metal covering for the wall. Each of these covers has adjacent thereto a sheathing 3 of heat-insulating material, such as magnesium board or asbestos board, or the like, molded into suitable sheets. My invention may be conveniently embodied in panels, each panel having, between the opposite wall sections 1, 50 3 and 2, 3 thereof, an upper spacing and frame member 4, a lower spacing and frame member 5, and vertical spacing and frame members 6. In addition to the upper and lower members 4 and 5, each panel may have 55 one or more intermediate horizontal mem-

bers 7 and one or more vertical members 8, according to the dimensions of the panel and the frequency of the bracing required between the opposed sides of the wall or panel.

For the members 4, 5, 6, 7 and 8, I employ 60 insulating material to which the opposite sides of the panel may be secured by means of nails. For such members I prefer to use resilient asbestos board, made by mixing the ingredients thereof and compacting the 65 mixture into stanchion shape with a press. By using such material for the spacing and frame members, I am enabled to form a wall or panel by securing the opposed wall sections 1, 3 and 2, 3 to such mem- 70 bers by such cheap and ordinary fastening means as nails or screws. As walls or panels of this general character have been constructed heretofore, angle irons have been used for the purpose of spacing apart 75 and bracing the opposed sides or sections of the walls or panels. This is objectionable, not only because of the weight, but because of the expense incurred in securing the opposite sides of the walls to such angle iron 80 members.

In Fig. 1, a corner of an oven or heat- 85 treating construction is shown. In making such corner, a special shape is given to the ends of the adjacent wall sections or panels. It will be noted that the metal sheet 1^a and the lining or sheathing 3^a are longer than the sheet 2^a and lining or sheathing 3^b. The same is true as to the length of the sheet 1 and lining or sheathing 3 as compared 90 with the length of the opposed sheet 2 and lining or sheathing 3. This enables the ends to be readily assembled into a corner, using vertical stanchions 6 and 6^a as a composite corner joist.

95 For the ordinary panels, other than corner panels, the two opposite sides 1, 3 and 2, 3 will be of the same length—see Fig. 3, and the metal covers 1 and 2 and the sheathings 3 will be extended beyond their adjacent vertical frame members 6, and, if necessary, in like manner beyond the uppermost and lowermost horizontal frame members 6. The metal covering, however, will be extended still further, in order that a 100 rolled or curled joint may be formed between adjacent panels, as indicated at 9.

A wall for the purposes specified may, of course, be built complete, in the same manner as a single panel; or it may be 110

built up from a number of panels, assembled in the manner indicated in Fig. 3 and with the corners formed as shown in Fig. 1.

A wall or panel constructed in accordance 5 with my invention has the advantage that it is comparatively cheap of production, is light in weight (thus minimizing the cost of transportation), may be readily assembled on the job, and affords an effective heat 10 insulation between the inner and outer surfaces of the wall. The use of the particular kind of material for stanchions or spacing and framing members enables me to use cheap screws or nails for fastening the composite 15 sides to the said braces or stanchions; and I am enabled to obtain all the necessary rigidity and insulation without the use of metal angles for the braces or stanchions.

The air space between the stanchions and 20 the sides of the partition or wall may be filled with any suitable insulating or non-conducting material, such as magnesium board, air-cell board, etc.

Having thus described my invention, what 25 I claim is:

1. A wall construction comprising an intermediate frame work of resilient asbestos board having applied to opposite sides thereof wall sections each having an external 30 sheet metal covering and an internal layer or sheathing of insulating material, the said wall sections being secured to the said frame work.

2. A wall construction comprising an intermediate frame work of insulating material having applied to opposite sides thereof wall sections each having an external sheet metal covering and an internal layer of insulating material, the said wall sections being 40 secured to the said frame work.

3. A wall construction comprising a plurality of horizontally arranged stanchions and a plurality of vertically arranged stanchions constituting an intermediate 45 frame work, the said stanchions being formed of resilient asbestos board, and opposed wall sections secured to said stanchions, each section comprising an outer sheet metal covering and an inner layer of insulating material, and screws or nails fastening the said wall sections to the said stanchions.

4. A wall construction comprising a plurality of horizontally arranged stanchions and a plurality of vertically arranged 55 stanchions constituting an intermediate

frame work, the said stanchions being formed of insulating material capable of receiving and sustaining a screw, and opposed wall sections secured to said stanchions, each 60 section comprising an outer sheet metal covering and an inner layer of insulating material, and screws or nails fastening the said wall sections to the said stanchions.

5. A wall section or panel comprising upper, lower and side members or stanchions of resilient asbestos board, and opposed wall sections secured to the said stanchions, each wall section comprising an external sheet metal covering and an inner insulating 70 sheathing, the ends of the sheet metal coverings and of their cooperating sheathings projecting beyond the stanchions adjacent thereto and the ends of the coverings projecting beyond their respective sheathings, 75 whereby the projecting metal ends of one such panel may be secured to the projecting metal ends of an adjacent panel.

6. A wall section or panel comprising upper and lower and side members or stanchions of insulating material, a wall section secured to the said stanchions, said section comprising an external sheet metal covering and an inner insulating sheathing, the ends of the sheet metal covering projecting beyond the ends of the sheathing, whereby the projecting metal ends of one such panel may be secured to the projecting metal ends of an adjacent panel.

7. A wall section or panel comprising a marginal frame work of resilient insulating material, and a pair of wall sections secured to such frame work and comprising an outer sheet metal covering and an inner insulating sheathing, the ends of the sheet metal coverings projecting beyond the ends of the sheathing and beyond the frame members adjacent thereto, whereby the ends of the sheathing of one panel are adapted to abut against the ends of the sheathing of the adjacent panel and the sheet metal ends of said panels may be united by a double-rolled bead.

8. A wall section or panel comprising a marginal frame work of resilient insulating material, and a wall section secured to such frame work and comprising an outer sheet metal covering and an inner insulating sheathing.

In testimony whereof, I hereunto affix my signature.

JOHN W. LATIMER.
